DUO-MODE WAVE ENERGY FEED

Robert S. Elliott, Los Angeles, Calif., assignor to Hughes Aircraft Company, Culver City, Calif., a corporation of Delaware

Application September 4, 1956, Serial No. 607,641

6 Claims. (Cl. 333—21)

This invention relates to duo-mode wave energy feeds and more particularly to a wave energy transducer which provides wave energy in a combination of the principal TEM-mode and the TE₁₀-mode of the coaxial waveguide.

In certain applications, wave energy antennas may be called upon to radiate an elliptically polarized beam of wave energy. Such antennas need be adapted to both receive and radiate wave energy polarized in two mutually perpendicular planes, and require feed means capable of exciting wave energy polarized in two mutually perpendicular planes. An adequate feed means is one adapted to excite wave energy in two modes having their respective electric field vector at right angles to one another.

An example of an antenna adapted to radiate and receive elliptically polarized wave energy is an omnidirectional surface wave beacon antenna having a dielectric clad metallic surface. To utilize the properties of this antenna, a coaxial waveguide feed is used to supply the dielectric trapping agent with elliptically polarized wave energy of high power. One way to obtain the desired cross components of wave energy is to excite wave energy in the coaxial feed waveguide in two modes, namely the TEM-mode and the TE₁₀-mode.

It is therefore an object of this invention to provide a wave energy feed which is adapted to excite wave energy in a combination of the TEM-mode and the TE₁₀-mode of a coaxial waveguide at its output end.

It is a further object of this invention to provide a device which, upon being excited, wave energy in the dominant TE₁₀-mode of the rectangular waveguide transforms the excited mode into the TE₁₀-mode of a coaxial waveguide and intermixes the wave energy in the transformed mode with wave energy in the TEM-mode of the coaxial waveguide.

It is a still further object of this invention to provide a new and novel duo-mode feed waveguide capable of providing wave energy in a combination of substantially pure TEM and TE₁₀-modes of the coaxial waveguide without the employment of interposed excitation elements which feed waveguide is simple in operation and capable of handling large amounts of power.

In accordance with this invention, a duo-mode wave energy feed having two input and one output terminal couples a rectangular input waveguide adapted to propagate wave energy in the dominant TE₁₀-mode and a coaxial input waveguide adapted to propagate wave energy in the principal TEM-mode to a coaxial output waveguide adapted to propagate wave energy in the duo-mode comprising the combination of the TEM-mode and the TE₁₀-mode. The duo-mode waveguide feed of this invention has a double function, namely to reorient the TE₁₀-mode of the rectangular input waveguide in progressive incremental stages until the electric field of the TE₁₀-mode of the coaxial output waveguides is obtained and thereafter to intermix the TE-mode and the TEM-mode of the coaxial input waveguide without generating higher order modes.

2

The TE₁₀-mode of the rectangular input waveguide is transformed by the duo-mode wave energy feed to the TE₁₀-mode of the coaxial output waveguide by first dividing the wave energy in the dominant TE₁₀-mode into two portions of equal amplitude having their respective electric field vectors E parallel and 180 degrees out of phase with one another. The electric field of each of the two portions of the wave energy is then progressively deformed to assume the familiar circularly symmetric pattern of the TE₁₀-mode of the coaxial waveguide in the final stage of reorientation. Finally after combining the two reoriented portions, the wave energy in the TE₁₀-mode of the coaxial waveguide and wave energy from the coaxial input waveguide are intermixed.

15 The novel features which are believed to be characteristic of the invention, both as to its organization and method of operation, together with further objects and advantages thereof, will be better understood from the following description considered in connection with the accompanying drawings in which several embodiments of the invention are illustrated by way of example. It is to be expressly understood, however, that the drawings are for the purpose of illustration and description only, and are not intended as a definition of the limits of the invention.

20 Fig. 1 is a cross-sectional view of one embodiment of the duo-mode wave energy feed in accordance with this invention;

25 Fig. 2 is a cross-sectional view taken along line 2—2 of the duo-mode wave energy feed of Fig. 1;

30 Fig. 3 is a three-dimensional view of the evolute of the duo-mode wave energy feed of Fig. 1;

35 Fig. 4 is a three-dimensional view of an alternate embodiment of the input portion of the duo-mode wave energy feed of Fig. 1; and

40 Fig. 5 is a three-dimensional exploded fragmentary view of the duo-mode wave energy feed of Fig. 1 showing the orientation of the electric field vector in progressive stages.

Referring now to the drawings and particularly to Fig. 40 thereof, there is shown one embodiment of the duo-mode wave energy in accordance with this invention wherein there are sequentially coupled to one another a dividing means such as the hybrid T 10, an electric field reorientation means 12, and a combining means 14. The hybrid T 10 has a sum arm 20, a difference arm 22 and two symmetry arms 24 and 26 respectively, and is adapted to propagate wave energy in the dominant TE₁₀-mode of the rectangular waveguide. The difference arm 22 is coupled to a rectangular input waveguide not shown in the drawing. Wave energy supplied to the difference arm 22 from a rectangular input waveguide is coupled to the two symmetry arms 24 and 26 in equal proportion and of opposite phases as is well known in the art.

45 The electric field orientation means 12 essentially comprises an evolute 28 surrounded by a cylindrical housing 30 and abuts against a circular end-plate 32 which is provided with openings to permit wave energy from the symmetry arms 24 and 26 to enter the field reorientation means 12. The evolute 28 comprises essentially a pair 50 of identical flutes 34 and 36 rigidly fastened to the outer conductor 38 of a waveguide 40. The outer conductor 38 and the cylindrical housing 30 also form a coaxial waveguide which is radially divided by the flutes 34 and 36 into two waveguides 42 and 44 which progressively change in cross-section from substantially rectangular to semi-circular.

55 The combining means 14, which is coupled to the electric field reorientation means 12 comprises a spline filter 46 surrounded by the cylindrical housing 30 having its vanes or fins 48 rigidly and radially fastened to the outer conductor 50 of a centrally located coaxial

waveguide 52. The coaxial waveguides 40 and 52 are of equal dimension and actually form a single continuous coaxial waveguide. The inner conductor 54, extending throughout the whole length of the evolute 28 and the spline filter 46, may be supported by teflon washers 56 and 58. The outer conductor 50 and the cylindrical housing 30 may be regarded as forming a coaxial waveguide which is an extension of the coaxial waveguide formed by the outer conductor 38 and the cylindrical housing 30. The radial vanes or fins 48 divide this waveguide into a plurality of sectoral waveguides each capable of propagating wave energy in the TE_{10} -mode. The spline filter 46 is terminated by tapering the radial fins 48 from the end portion 60 of the outer conductor 50 gradually in the form of a trailing edge 62 to the cylindrical housing 30. In this manner the trailing edges 62 of the spline filter 46 form an inverted cone and provide for a wave energy transition from the coaxial waveguide 52 to a new coaxial waveguide 64 formed by the inner conductor 54 and the cylindrical housing 30. In other words the trailing edges 62 of the spline filter 46 provide a smooth wave energy transition between two coaxial waveguides of different dimensions.

Fig. 2 is a cross-sectional end view taken along the line 2--2 of Fig. 1 and shows with greater particularity the details of the end plate 32. The end plate 32 is provided with two rectangular openings 70 and 72 to which are coupled the symmetry arms 24 and 26 of the hybrid T 10, respectively. The openings 70 and 72 become one of the end portions of the progressively widening waveguides defined by the flutes 34 and 36, respectively. The opening 74 at the center of the end plate 32 permits access to the coaxial waveguide 40, to which is coupled a coaxial input waveguide 76 shown in Fig. 5. Fig. 2 further shows the direction and the relative phase of the electric field vectors E of the wave energy upon entering the electric field reorientation means 12.

Fig. 3 is a three-dimensional view of the evolute 28 of the duo-mode wave energy feed of Fig. 1, showing with greater particularity its geometrical configuration. Two flutes 34 and 36 are attached to outer conductor 38 of the coaxial waveguide 40. The sectoral space lying between the flutes 34 and 36 provides the progressively widening waveguides 42 and 44 defined by the side walls of the flutes 34 and 36, the outer conductor 38 and the cylindrical housing 30 shown in Fig. 1. The progressively widening waveguides 42 and 44 have a substantially rectangular cross-section at the end portion 82 and a substantially semi-circular cross-section at the end portion 84. The change of waveguide cross-section from one end portion to the other end portion is gradual and smooth and not critical. The length of the evolute 12 is determined solely by considerations of how perfect a transformation is desired. Shorter evolute length requires a steeper shape of the flute walls and greater impedance mismatch, which is attended with the possible generation of higher order modes.

Fig. 4 is a three-dimensional view of a different embodiment of the dividing means which may be used instead of the hybrid junction 10 of Fig. 1. A rectangular waveguide 90 is coupled to a Y-type power divider 92 which has two output waveguides 94 and 96, respectively. The output waveguides 94 and 96 are each twisted through an angle of 90 degrees so that a relative rotation of 180 degrees results. The output waveguides 94 and 96 may be joined to the end plate 32 in the same manner as the symmetry arms 24 and 26 of Fig. 1. The rectangular waveguide 90 may be coupled to the rectangular input waveguide not shown in the drawings. Fig. 4 also shows the relative orientation and phase of the electric field vector E at the input end of the waveguide 90 and at the output ends of waveguides 94 and 96, respectively. Wave energy which enters the rectangular waveguide 90 is split up into two equal components by the power divider 92 and rotated 180 degrees

with respect to one another in the twisted output waveguides 94 and 96.

Fig. 5 is a three-dimensional exploded view of the duo-mode wave energy feed of Fig. 1 showing in progressive stages the reorientation or deformation of the electric field vector E, and is included to aid in the explanation of this invention. The electric field vector is shown on the drawings as a heavy line with an arrow indicating its relative phase. Wave energy from a rectangular input waveguide which is coupled to the difference arm 20 of the hybrid T 10 is split up into two components of equal magnitude which are 180 degrees out of phase with one another. The perspective view of the end plate 32 shows the relative orientation of the electric field vectors E in the symmetry arms 24 and 26 respectively. A coaxial input waveguide 76 propagating the principal TEM-mode is coupled to the opening 74 of the end plate 32 which in turn couples to the coaxial waveguide 40. Wave energy enters progressively widening waveguides 42 and 44 in the TE_{10} -mode from the symmetry arms 24 and 26 where in the electric field vector E changes its direction from that of a straight line to that of a semi-circle which semi-circle is complete when the end portion of the evolute 28 is reached. The spline filter 46 freely passes wave energy in the TE_{10} -mode of the coaxial waveguide but no higher order modes and therefore eliminate all higher modes which may be generated in the progressively widening waveguides 42 and 44 due to impedance mismatch. After transmission through the spline filter 46 a pure TE_{10} -mode is obtained in the output means 16.

The principal TEM-mode propagated through the coaxial waveguide 40 and 52 is expanded or exploded with the aid of the tapered or trailing edges 62 of the individual vanes 48 of the spline filter 46. As mentioned before this expansion or explosion of the outer conductor 50 into coincidence with the cylindrical housing 30 is similar to a conical transition between two coaxial waveguides of different diameters. After the exploding of the wave energy in the principal TEM-mode an intermixing of the exploded wave energy with the wave energy in the TE_{10} -mode takes place. In this manner the coaxial output waveguide 64 provides wave energy having a combination of the principal TEM-mode and the TE_{10} -mode of the coaxial waveguide.

The duo-mode wave energy feed in accordance with this invention therefore provides at its output end the principal TEM-mode and the TE_{10} -mode of the coaxial waveguide intermixed with one another. The input end of the duo-mode wave energy is coupled to a rectangular input waveguide adapted to supply wave energy in the TE_{10} -mode and to a coaxial input waveguide adapted to supply wave energy in the principal TEM-mode. The wave energy mode transition from the TE_{10} -mode of the rectangular waveguide to the TE_{10} -mode of the coaxial waveguide taking place within the duo-mode wave energy feed is a unity transition and consequently this feed may be employed when high power transmission and broad band operation is required.

What is claimed is:

1. A duo-mode wave energy feed having a coaxial output waveguide member adapted to provide a predetermined combination of wave energy in the TE_{10} -mode and the TEM-mode and comprising: dividing means for dividing wave energy in the dominant TE_{10} rectangular waveguide mode into two substantially equal portions and including means to impart a 180 degree relative phase shift between said portions; electric field orientation means coupled to said dividing means for combining said two portions of wave energy to form the TE_{10} -mode of a coaxial waveguide; a coaxial input waveguide having an outer and an inner conductor; a spline filter within a cylindrical housing having radial vanes extending from said outer conductor and coupled to said electric field reorientation means, one end of said vanes having a trailing edge extending beyond said outer conductor and

effectively expanding said outer conductor into coincidence with said cylindrical housing, said inner conductor and said outer conductor subsequent to expansion and coincidence with said cylindrical housing defining said coaxial output waveguide member.

2. A duo-mode wave energy feed having a coaxial output waveguide member adapted to provide a predetermined combination of wave energy in the TE_{10} -mode and the TEM-mode and comprising: dividing means for dividing wave energy in the dominant TE_{10} rectangular waveguide mode into two substantially equal portions and including means to impart a 180 degree relative phase relation between said portions; electric field orientation means coupled to said dividing means for combining said two portions of wave energy into the TE_{10} -mode of a coaxial waveguide; a coaxial input waveguide adapted to provide wave energy in the TEM-mode having an inner and an outer conductor, a cylindrical housing coaxially surrounding said outer conductor and defining a coaxial waveguide, said coaxial waveguide being coupled to said electric field reorientation means; and expansion means coupled to said outer conductor for coaxially expanding said outer conductor into coincidence with said cylindrical housing, said expanded outer conductor and said inner conductor defining said coaxial output waveguide member.

3. A duo-mode wave energy feed having a coaxial output waveguide member adapted to provide a predetermined combination of wave energy in the TE_{10} -mode and the TEM-mode and comprising: dividing means including a rectangular input waveguide for feeding wave energy in the TE_{10} -mode into said dividing means, said dividing means adapted to divide said wave energy in the TE_{10} -mode into two substantially equal portions, said dividing means including an element for separately and oppositely rotating each of said two portions of wave energy through an angle of 90 degrees; electric field reorientation means responsive to said rotated portions of wave energy coupled to said dividing means and adapted to combine said two rotated portions of wave energy to provide the TE_{10} -mode of the coaxial waveguide; a coaxial input waveguide having an outer and an inner conductor and a spline filter within a cylindrical housing having radial vanes extending from said outer conductor coupled to said electric field reorientation means, one end of said vanes defining an inverted cone and effectively exploding said outer conductor into coincidence with said cylindrical housing, said coaxial input waveguide adapted to feed wave energy in the TEM-mode through the central portion of said spline filter, said inner conductor and said outer conductor subsequent to expansion and coincidence with said cylindrical housing defining said coaxial output waveguide member.

4. A duo-mode wave energy feed having a coaxial output waveguide member adapted to provide a predetermined combination of wave energy in the TE_{10} -mode and the TEM-mode and comprising: a rectangular Y-type power divider having two rectangular output ports; two mirror image rectangular waveguide sections each twisted in opposite rotational sense through an angle of 90 degrees and each coupled to a different one of said output ports whereby said mirror image waveguide sections provide wave energy in the dominant TE_{10} -mode having their respective field vectors 180 degrees out of phase with one another; a coaxial input waveguide having an outer and an inner conductor and adapted to provide wave energy in the TEM-mode; an evolute contained within a cylindrical housing having two radial flutes of progressively changing cross-section extending from said outer conductor, the surfaces of said outer conductor, said housing and said flutes defining two substantially identical progressively widening waveguides whose cross-sectional area changes smoothly from substantially rectangular to substantially semi-circular, said two progressively widen-

ing waveguides each coupled to a different one of said mirror image waveguide sections; and a spline filter within a cylindrical housing having radial vanes extending from said outer conductor coupled to said evolute, one end of said vanes defining an inverted cone and effectively exploding said outer conductor to coincidence with said cylindrical housing, said inner conductor and said outer conductor subsequent to explosion and coincidence with said cylindrical housing defining said coaxial output waveguide member.

5. A duo-mode wave energy feed having a coaxial output waveguide member adapted to provide a predetermined combination of wave energy in the TE_{10} -mode and the TEM-mode and comprising: a hybrid T having a difference arm for feeding wave energy into said hybrid T and two symmetry arms for providing substantially equal portions of wave energy in the TE_{10} rectangular waveguide mode having a 180 degree out of phase relationship between respective electric field vectors; a coaxial input waveguide having an inner and an outer conductor and adapted to provide wave energy in the TEM-mode; an evolute contained within a cylindrical housing having two flutes of progressively changing cross-section extending from said outer conductor, the space defined by said outer conductor, said housing and said flutes providing two progressively widening waveguides whose cross-sectional area changes progressively from substantially rectangular to substantially semi-circular, said two progressively widening waveguides being coupled to a different one of each of said two symmetry arms; and a spline filter within a cylindrical housing having radial vanes extending from said outer conductor, one end of said vanes defining an inverted cone and effectively bringing said outer conductor into coincidence with said cylindrical housing, said inner conductor and said outer conductor subsequent to coincidence with said cylindrical housing defining said coaxial output waveguide member.

6. A duo-mode wave energy feed having a coaxial output waveguide member adapted to provide a predetermined combination of wave energy in the TE_{10} -mode and in the TEM-mode, said wave energy feed comprising: a coaxial waveguide having an inner and an outer conductor and adapted to be excited in the TEM-mode, a cylindrical housing axially surrounding said outer conductor, a pair of flutes of progressively changing cross-section extending radially from one portion of said outer conductor and longitudinally dividing the space between said outer conductor and said cylindrical housing into two wave propagation paths each having a cross-sectional area which changes progressively from a substantially rectangular area defining the input end to a substantially semi-circular area forming the output end of said waveguide propagation paths, feed means coupled to said input end of said propagation paths and adapted to feed each of said wave propagation paths an equal amount of wave energy in the TE_{10} rectangular waveguide mode whose electric fields have a 180 degree relative phase relation with respect to one another, a set of radial vanes extending from another portion of said outer conductor and extending to said cylindrical housing, said vanes each having trailing edges which define the surface of an inverted frustum of a right circular cone, said trailing edges gradually exploding said outer conductor into coincidence with said cylindrical shell, the inner conductor of said first coaxial waveguide and said exploded outer conductor defining said coaxial output waveguide.
